UNITED STATES PATENT OFFICE.

ROBERT WOOD, OF NEW YORK, N. Y., ASSIGNOR TO THE NATHAN MANUFACTURING COMPANY, OF NEW YORK, N. Y., A CORPORATION OF NEW YORK.

LUBRICATOR.

1,158,614.

Specification of Letters Patent.

Patented Nov. 2, 1915.

Application filed November 14, 1913. Serial No. 800,976.

To all whom it may concern:

Be it known that I, ROBERT WOOD, a subject of the King of Great Britain and Ireland, residing at 435 East Fourth street, 5 borough of Brooklyn, city of New York, in the county of Kings and State of New York, have invented certain new and useful Improvements in Lubricators, of which the following is a specification.

10 This invention relates to force feed lubricators for locomotives. Its novelty consists in the construction and adaptation of the parts, and the result is a lubricator operated in synchronism with the admission of 15 steam to the cylinders and delivering oil to such cylinders through sight feed chambers devoid of pressure; one capable of lubricating an air pump when the cylinders are not operated, as while coasting or standing 20 still, one which has few and simple parts which are readily made or replaced, has no actuating springs and is capable of accurate adjustment.

In the drawings, there is shown a preferred form of device embodying the invention, but it will be understood that variations may be made in the proportion and somewhat in the arrangement of the parts without departing from the principles of 30 the invention.

In the drawings, Figure 1 is a view of a locomotive showing a general method of attaching the lubricator thereto; Fig. 2 is a front elevation of a preferred form of the 35 device on an enlarged scale; Fig. 3 is a top plan view of the parts shown in Fig. 2; Figs. 4 and 5 are vertical transverse sections on the planes of the lines 4-4 and 5-5, respectively, of Fig. 3, and Fig. 6 is a perspective detail of the connection between the rocking arm and the return piston.

In the drawings, 10 indicates a locomotive of usual form provided with two cylinders 11, one on each side (only one being shown), 45 each supplied with steam from the boiler through pipe connections indicated at 12. There is also provided a usual form of air pump indicated at 13 for supplying compressed air to the brake system. At any 50 convenient place within the cab 14 is located the lubricator which comprises, among other parts, an external casing 15 adapted to contain the other parts, and

which is divided in the particular device shown, into four parts, viz., an actuator indicated generally at 16, and three feeding devices indicated, respectively, at 17, 18 and 19. A steam supply pipe 20 leads from the steam dome to the upper part of the actuator through the usual insulation of the 55 boiler shell to conserve its heat. A second steam supply pipe 21 leads from one of the cylinders 11 near its admission port, for instance, from the indicating plug through the shell covering of the boiler to a three 60 way cock 22 which is provided with an operating handle 23 and which controls a pipe 24 leading to the lower part of the actuator. Three oil feed pipes 27, 28 and 29 lead respectively, from the feeding devices 17, 18 65 and 19 to the air pump 13, the service pipe 12 of the right hand cylinder 11, and the similar supply pipe of the left hand cylinder. These pipes are all placed close to the steam conveying pipes and preferably 70 through the insulated shell of the boiler in order to effect an interchange of the heat 75 and deliver the oil to the cylinders at the proper temperature. A branch pipe 25 leads from the steam end of the air pump 80 13 to the three way cock 22. These pipes conveying steam and oil are shown in dotted outline only in Fig. 1 in order to avoid confusion.

We will next describe the actuator, which 85 is in effect a species of pump. There is arranged at a convenient point within the casing 15, a cylinder 30 which contains a large bore 31 adapted to receive a piston 32 and a reduced bore adapted to receive a push rod 90 33 made integral with or secured to the piston. The cylinder may be secured in place by any convenient means as an expanded flange 34 adapted to engage one wall, and an annular cap flange 35 adapted 95 to engage the other wall, of the casing 15. At its large open end this cylinder is connected by a union 36 to the steam inlet pipe 24. At another convenient point in the casing there is arranged a second cylinder 37 100 having a uniform bore and adapted to contain a piston 38 and connected at one end by a union 39 to the steam inlet pipe 20. It will be noted that the cross sectional area of the piston 32 is much greater than that 105 of the piston 38. Suspended across the cas-

ing 15 is a rock shaft 40 on which is keyed a lever 41 adapted to be engaged by the end of the push rod 33 beneath the shaft and the upper end of which, above the shaft, is provided with a fork 42 having slots 43 to receive a transverse pin 44 secured to one end of the piston 38. At one end the rock shaft is provided with a hand wheel 45 by which, when desired, it can be manually manipulated.

All of the three feeding devices are alike in their main features and we will only describe in detail the one 18 which supplies oil to the right hand cylinder 11. This device is shown in section in Fig. 5. Arranged adjacent to one wall of the casing 15 is a housing 50 provided at a convenient place with a projecting cylinder 51 extending through and across the casing and held in place by an apertured cap flange 52. The cylinder 51 contains a piston 53 which, at one end, is provided with a transverse pin 54 adapted to engage slots 55 formed in a forked end 56 of a rocking arm 57 keyed to the shaft 40. At its opposite end the piston 53 is reduced to form a ram 58 adapted to reciprocate in a bore 59 formed in the housing 50.

Near the bottom of the casing there is a port 60 leading to a vertical channel 61 which leads in turn to the bottom of the interior of the cylinder 51 and serves as an oil inlet for the cylinder. Above the cylinder a similar channel 62 which serves as an oil outlet for the cylinder, leads to a cross passage 63 which leads in turn to an oil reservoir 64 formed in the housing. A check valve, indicated at 65, is placed in the channel 61 near its lower end, and between this valve and the cylinder 51 is arranged a cylindrical cut-off valve 66. At the top of the channel 62 is a spring pressed check valve 67 having a piston 68 adapted to fit within a tubular bore 69 provided for the purpose and which piston serves normally to close the entrance to an overflow channel 70 leading back through the wall of the casing 15 into its interior. If for any reason the oil coming up through the channel 62 should press upward too far it would force back the piston 68 and pass through the overflow channel indicated.

A set valve 71 having a conical tip is adapted to engage the upper rim of an outlet passage 72 provided at the bottom of the reservoir 64. This valve is screw-threaded into a plug 73 at the top of the housing 50 and having a squared tip 74 is readily adjusted from the outside. The outlet passage 60 72 leads to a sighting chamber 75 provided with one or more transparent windows 76 (preferably made of mica) held in position in threaded frames 77 screwed into the housing. Beneath this chamber 75 there is an outlet to another chamber 78 controlled by

a spring pressed check valve 79 and connected in turn by a passageway 80 provided with one or more check valves 81 to the pipe 28, a union 82 securing such pipe to a nipple 83 threaded into the casing. 76

The three way cock 22 when turned is adapted to shut off the steam coming from the cylinder 11 through the pipe 21 and to turn on the steam coming from the air pump steam supply through the pipe 25, it being understood that the inlet from the pipe 25 is closed and that from the pipe 21 is open, and vice versa.

There are two cut-off valves 66, one in each feeding device 18 and 19. They are connected together by a short shaft 85 to which at one end is secured a crank 86 secured in turn to a link 87 pivoted to a crank 88 secured to the plug 89 of the three way cock 22. By this mechanism whenever the handle 23 is turned to shut off steam from the pipe 21 coming from the cylinder 11, simultaneously and automatically the valves 66 are turned and close the channels 61 in the feeding devices 18 and 19 leading to these cylinders so that no oil can be supplied to these cylinders while the engine is not running.

It will be understood that there are no cross partitions in the casing 15. It constitutes a continuous chamber across which are arranged the cylinders 30 and 37 of the actuator and the three cylinders 51 of the feeding devices. The oil is placed into the casing through a plug 90 having a strainer 91. 100

A steam exhaust pipe 92 is provided beneath the cylinder 30 (see Fig. 4).

The operation of the device is as follows: It will be assumed that the interior of the casing has been supplied with a proper quantity and quality of oil, that the locomotive is running normally and that the three way cock 22 is turned to admit steam from the pipe 21 through the cock and branch pipe 24 into the actuator cylinder 110 30. This steam comes from the cylinder 11 under the pressure existing in it when it is introduced into the cylinder 11, there being practically no loss of either pressure or heat in its travel through the pipe 21 as the latter is in the insulated shell of the boiler. The steam being admitted to the cylinder 30 pushes the piston 32 toward the left (see Fig. 4) and moves the push rod 33 in the same direction. This rod contacts with the lower end of the rocking arm 41 and rocks the shaft 40 to the left or clockwise. As soon as this movement takes place, each of the pistons 53 connected to the rocking levers 57 also keyed to the shaft 40 (see Fig. 5) are moved to the right and as they move, if there is any oil in the bore 59 and passageway 80, it is forced forward by the action of the ram 58 past the valves 81 into the pipe 28. When the piston within the 136

cylinder 11 reaches a certain position within such cylinder the steam coming into the cylinder through the pipe 12 (or directly from the steam space within the boiler) is cut off by the usual slide valve provided for that purpose, and the pressure of the steam in the supply pipe 21 and branch pipe 24 of course falls accordingly. In the meantime, however, it will be observed there has been 10 a free communication through the pipe 20 from the steam dome of the boiler to the right end of the piston 38 in the cylinder 37 of the actuator (see Fig. 4). This steam is at a constant pressure equal, of course, to the initial pressure of the steam in the pipes 21 and 24. As soon, therefore, as the pressure on the piston 32 falls to a point, considering its cross sectional area, that is less than the pressure on the piston 38, the latter moves toward the left and, acting upon the forked end 42 of the rocking arm 41 through the pins 44, rocks the shaft 40 anti-clockwise and forces the piston 32 back to its initial position, any steam in the cylinder 25 which passes the end of the piston 32 passing out through the pipe 92. As soon as the shaft 40 is rocked in this direction each of the pistons 53 are moved toward the left and create a suction in the cylinder 51 30 which draws the oil from the interior of the casing 15 through the port 60, the check valve 65, channel 61 and cut-off valve 66 into the cylinder 51. As soon as steam is again admitted to the pipe 21 the actuator 35 piston 32 is again moved to the left notwithstanding that such movement is against a volume of steam of equal pressure through the pipe 20 upon the piston 38 because the cross sectional area of the piston 38 is made 40 less than that of the piston 32 for precisely such purpose of making the resultant pressures on the pistons unequal. When this movement takes place the piston 38 is returned to its initial position, and so are all 45 of the pistons 53. But the latter pistons in their movement to the right not only move their rams 58 to force the oil to the pipe 28, but the right faces of these pistons moving along their cylinder, force the oil which has 50 been drawn into such cylinders out of them and into the channels 62, it being prevented from going back through the channel 61 and port 60 by the check valve 65. From the channel 62 it is forced through the channel 55 63 into the reservoir 64 whence it is allowed to drop by gravity into the sighting chamber 75, past the valve 79, into the cylinder 78 and bore 59, whence, as before, it is forced through the pipe 28 to the cylinder 60 111 11.

It will readily be seen that by this device the actuator pumps the oil only so long as the steam is being admitted to the main engine cylinders. The moment the steam is 65 cut off from such cylinders its pressure falls

and soon the superior constant pressure of the steam upon the smaller cross sectional area of the actuator return piston overcomes such pressure and causes a return stroke. In other words, the actuator piston 70 is caused to work intermittently only while steam is admitted to the pistons.

There is no pressure in the sight chamber 75 because of the check valves controlling the passage of the oil, and as the windows 76 75 are made of mica they can not break from any changes of temperature.

Assuming that the device has been operated as stated, it will readily be seen that a constant supply of oil is being delivered 80 through the pipes 28 and 29 to the locomotive cylinder and through the pipe 27 to the air pump, such delivery synchronizing with the admission of steam thereto and being cut off when the steam is cut off. Also, 85 it will be seen that as the steam supply pipes are arranged alongside of the oil supply pipes there will be an interchange of heat tending to raise the temperature of the oil at the point of delivery to render it fit 90 for lubrication.

If the engine is stopped from any cause, no oil is needed for the cylinders 11, but oil is needed for the air pump 13. In such case the handle 23 of the three way cock 22 is 95 turned. This cuts off the steam to the branch pipe 24 from the pipe 21 and lets in the steam from the pipe 25 and the actuator is operated as before. But it also closes the valve 66 in each of the feeding devices 18 100 and 19 while it does not effect the device 17 which has no such valve. Consequently, while the cylinders 11 are no longer supplied with oil the pump 13 is supplied as before. When the engine is started again the cock 105 22 is turned back to its original position.

The hand wheel 45 enables the operator to rock the shaft 40 to operate the feeding devices if the actuator is not working so that the engine cylinders or the pump might 110 be lubricated although the steam supply were cut off. This hand manipulation also may prove useful in other ways.

It is obvious that the actual boiler pressure may vary between wide limits without 115 affecting the mode of operation of my device because it is the constant boiler pressure on a small piston as opposed to an identical intermittent pressure on a large piston which causes such operation.

From the fact that there is no pressure in the sight chamber I can use thin mica or glass windows which require no strength and which eliminate all errors of observation as to the amount of oil fed past the windows due to refraction in thick or curved glass.

It will be noticed by those skilled in the art obtained by means of the described apparatus a movement of the actuating device 120 125 130

of the lubricator which synchronizes with the time when the live steam is within the locomotive cylinder and that consequently there is an injection of oil into such cylinder during such period of steam admission. Also the gradual decrease in pressure inside of the cylinder containing the actuator piston when the cut-off takes place in the main cylinders provides an elastic cushion for such piston so that when the constant pressure of the steam is exerted to reverse its movement no jar is produced upon any of the parts of the device, but the movement is smooth and easy.

15 It should also be noted that by reason of the fact that both the intermittent and constant steam supply comes from the same source, viz: the boiler pressure, any variation in this pressure will not affect the operation of the device for the same relative pressures will always be exerted on the alternating parts no matter what the actual pressures may be. This enables me to dispense with springs and other complications in the production of the desired reciprocating movement and results in a simple and efficient device.

What I claim is:

30 1. In a lubricating device for engines, an actuator including a piston and means for supplying steam thereto at the same time and under the same pressure that it is supplied to the engine cylinders and cutting it off when it is cut off from such cylinders, and a second piston adapted to be moved in a reverse direction from that of the first piston and means for supplying steam thereto constantly from the boiler.

40 2. In a lubricating device for engines, an actuator including a piston and means for supplying steam thereto at the same time and under the same pressure that it is supplied to the engine cylinders and cutting it off when it is cut off from such cylinders, and a second piston adapted to be moved in a reverse direction from that of the first piston and means for supplying steam thereto constantly from the boiler, in combination with an oscillating device including a shaft.

50 3. In a lubricating device for engines, an actuator including a piston and means for supplying steam thereto at the same time and under the same pressure that it is supplied to the engine cylinders and cutting it off when it is cut off from such cylinders, and a second piston adapted to be moved in a reverse direction from that of the first piston, and means for supplying steam thereto constantly from the boiler, in combination with an oscillating device including a shaft adapted to be moved in one direction by the intermittent pressure of the steam on the first piston and in the opposite direction by the constant pressure of the steam on the second piston.

4. In a lubricating device for engines, an actuator including a piston and means for supplying steam thereto at the same time and under the same pressure that it is supplied to the engine cylinders and cutting it off when it is cut off from such cylinders, and a second piston adapted to be moved in a reverse direction from that of the first piston, and means for supplying steam thereto constantly from the boiler, in combination with an oscillating device including a shaft adapted to be moved in one direction by the pressure of the steam on the first piston and in the opposite direction by the pressure of the steam on the second piston.

5. In a lubricating device for engines, an actuator including a piston and means for supplying steam thereto at the same time and under the same pressure that it is supplied to the engine cylinders and cutting it off when it is cut off from such cylinders, and a second piston adapted to be moved in a reverse direction from that of the first piston, and means for supplying steam thereto constantly from the boiler, in combination with an oscillating device including a shaft adapted to be moved in one direction by the pressure of the steam on the first piston and in the opposite direction by the pressure of the steam on the second piston.

6. In a lubricating device for engines, an actuator including a piston and means for supplying steam thereto at the same time and under the same pressure that it is supplied to the engine cylinders and cutting it off when it is cut off from such cylinders, and a second piston adapted to be moved in a reverse direction from that of the first piston, and means for supplying steam thereto constantly from the boiler, in combination with an oscillating shaft adapted to be moved in one direction by the intermittent pressure of the steam on the first piston and in the opposite direction by the constant pressure of the steam on the second piston, the cross-sectional area of the first piston being greater than that of the second piston.

7. A lubricating device comprising an oil reservoir, a piston adapted to be reciprocated, a ram moved from the piston to force the oil from the reservoir, and means for moving the piston synchronously with the admission and cut off of steam to an engine cylinder including a second piston, a pipe adapted to conduct steam from the engine cylinder at its inlet port to such piston, and means for returning the second piston to its original position, consisting of a third piston, and a pipe adapted to conduct steam from the boiler thereto.

8. A lubricating device comprising an oil

- reservoir, a piston adapted to be reciprocated, a ram moved from the piston to force the oil from the reservoir, and means for moving the piston synchronously with the admission and cut off of steam to an engine cylinder including a second piston, a pipe adapted to conduct steam from the engine cylinder at its inlet port to such piston, and means for returning the second piston to its original position, consisting of a third piston and a pipe adapted to conduct steam from the boiler thereto, the third piston having a smaller cross-sectional area than the second piston.
15. 9. A lubricating device for a locomotive having two cylinders and an air pump, comprising three oil feeding devices one for each cylinder and the air pump, and an actuator adapted to cause the operation of the feeding devices operated in one direction by the steam from an engine cylinder or the pump and in the reverse direction by the steam from the boiler.
10. A lubricating device for a locomotive having two cylinders and an air pump, comprising three oil feeding devices one for each cylinder and the air pump, and an actuator adapted to cause the operation of the feeding devices operated in one direction by the steam from an engine cylinder or the pump and in the reverse direction by the steam from the boiler, in combination with means for cutting off the steam from the engine cylinder and turning it on from the air pump.
11. A lubricating device for a locomotive having two cylinders and an air pump, comprising three oil feeding devices one for each cylinder and the air pump, and an actuator adapted to cause the operation of the feeding devices operated in one direction by the steam from an engine cylinder or the pump and in the reverse direction by the steam from the boiler, in combination with means for cutting off the steam from the engine cylinder and turning it on from the air pump and simultaneously and automatically cutting off the oil feeding devices from the engine cylinders.
12. A lubricating device for a locomotive having two cylinders and an air pump, comprising three oil feeding devices one for each cylinder and the air pump, and an actuator adapted to cause the operation of the feeding devices operated in one direction by the steam from an engine cylinder or the pump and in the reverse direction by the steam from the boiler, in combination with means for cutting off the steam from the engine cylinder and turning it on from the air pump, said means including devices for cutting off the oil supply to the engine cylinders.
13. In a device of the character described, a plurality of oil reservoirs, pipes leading one from each reservoir, rams, one for each pipe adapted to force oil delivered by gravity from a reservoir into and through its pipe and means for operating the rams in unison by steam from the engine cylinders, and moving them to their initial position by steam from the boiler.
14. The combination with a locomotive of a plurality of oil reservoirs, a pipe from one reservoir to one engine cylinder, a pipe from a second reservoir to the other engine cylinder, rams one for each pipe adapted to force the oil forward from the reservoir along its pipe, and a cylinder and single piston therein for moving all the rams actuated by steam taken from an engine cylinder at the beginning of its stroke and cut off when it is cut off from the engine cylinder whereby the oil is fed to the engine cylinders only while the steam is being admitted thereto.
15. The combination with a locomotive of a plurality of oil reservoirs, a pipe from one reservoir to one engine cylinder, a pipe from a second reservoir to the other engine cylinder, rams, one for each pipe adapted to force the oil forward from the reservoir along its pipe, and means for moving the rams actuated by steam taken from an engine cylinder at the beginning of its stroke and cut off when it is cut off from the engine cylinder, whereby the oil is fed to the engine cylinders only while the steam is being admitted thereto and means constantly actuated on by steam from the boiler for returning the rams to their initial positions as soon as the steam ceases to be admitted to the engine cylinders.
16. The combination with a locomotive of a plurality of oil reservoirs, a pipe from one reservoir to one engine cylinder, a pipe from a second reservoir to the other engine cylinder, rams, one for each pipe adapted to force the oil forward from the reservoir along its pipe, and means for moving the rams actuated by steam taken from an engine cylinder at the beginning of its stroke and cut off when it is cut off from the engine cylinder, and means for returning the rams to their initial position when the steam is again admitted to the cylinder, such means including a piston subject to the constant pressure of the steam in the boiler.
17. The combination with a locomotive of a plurality of oil reservoirs, a pipe from one reservoir to one engine cylinder, a pipe from a second reservoir to the other engine cylinder, rams, one for each pipe adapted to force the oil forward from the reservoir along its pipe, and means for moving the rams actuated by steam taken from an engine cylinder at the beginning of its stroke and cut off when it is cut off from the engine cylinder, whereby the oil is fed to the engine cylinders only while the steam is being admitted.

- thereto and means for returning the rams to their initial positions as soon as the steam ceases to be admitted to the engine cylinders, such means including a piston subject to the constant pressure of the steam in the boiler.
18. The combination with a locomotive provided with an air pump, of a plurality of oil reservoirs, pipes from two of the reservoirs to the engine cylinders and from another reservoir to the air pump, rams, one for each pipe adapted to force the oil from the several reservoirs along their respective pipes, all of the rams being moved in common by an actuator including a reciprocating piston receiving steam from the inlet end of an engine cylinder so long as the steam is being admitted to such cylinder and cut off when the steam is cut off therefrom whereby such steam forces the piston in one direction, and means under constant steam pressure and opposing the action of the piston for returning the piston to its initial position.
19. The combination with a locomotive provided with an air pump, of a plurality of oil reservoirs, pipes from two of the reservoirs to the engine cylinders and from another reservoir to the air pump, rams, one for each pipe adapted to force the oil from the several reservoirs along their respective pipes, all of the rams being moved in common by an actuator including a reciprocating piston receiving steam from the inlet end of an engine cylinder so long as the steam is being admitted to such cylinder and cut off when the steam is cut off therefrom whereby such steam forces the piston in one direction, and means for forcing it in the opposite direction including a piston constantly receiving steam from the boiler.
20. The combination with a locomotive provided with an air pump, of a plurality of oil reservoirs, pipes from two of the reservoirs to the engine cylinders and from another reservoir to the air pump, rams, one for each pipe adapted to force the oil from the several reservoirs along their respective pipes, all of the rams being moved in common by an actuator including a reciprocating piston receiving steam from the inlet end of an engine cylinder or from the pump, and means for supplying steam from either source.
21. The combination with a locomotive provided with an air pump, of a plurality of oil reservoirs, pipes from two of the reservoirs to the engine cylinders and from another reservoir to the air pump, rams, one for each pipe adapted to force the oil from the several reservoirs along their respective pipes, all of the same being moved in common by an actuator including a reciprocating piston receiving steam from the inlet end of an engine cylinder or from the pump, and means for supplying steam from either

source, and when supplied from the pump automatically cutting it off from the engine cylinder supply pipes.

22. A sight feed lubricator for locomotives or the like comprising a plurality of feed devices each including a ram and common means for moving all of the rams in unison including two pistons, one adapted to receive steam intermittently as the steam is fed to the engine cylinders, and the other adapted to receive steam constantly from the boiler.

23. A sight feed lubricator for locomotives or the like comprising a plurality of feed devices, each including a ram and common means for moving all of the rams in unison including two pistons, one adapted to receive steam intermittently as the steam is fed to the engine cylinders, and the other adapted to receive steam constantly from the boiler, the first piston being of larger cross sectional area than the second piston.

24. A lubricating device comprising a casing, inclosing an oil reservoir, a plurality of housings, each containing an oil feeding device in proximity thereto and each adapted to receive oil from the common reservoir, rams, one for each housing arranged across the casing, levers, one for each ram all mounted on a common shaft outside the casing and means for rocking the shaft to reciprocate the rams.

25. A lubricating device comprising a casing, inclosing an oil reservoir, a plurality of housings, each containing an oil feeding device in proximity thereto and each adapted to receive oil from the common reservoir, rams, one for each housing arranged across the oil reservoir, levers, one for each ram all mounted on a common shaft outside the reservoir and means for rocking the shaft to reciprocate the rams including a manually operated wheel outside of the casing.

26. A lubricating device comprising a casing, inclosing an oil reservoir, a plurality of housings, each containing an oil feeding device in proximity thereto and each adapted to receive oil from the common reservoir, rams, one for each housing arranged across the casing, levers, one for each ram all mounted on a common shaft and means for rocking the shaft to reciprocate the rams including two pistons, one adapted to receive steam intermittently as the steam is fed to the engine cylinders, and the other adapted to receive steam constantly from the boiler.

27. A lubricating device comprising a casing, inclosing an oil reservoir, a plurality of housings, each containing an oil feeding device in proximity thereto and each adapted to receive oil from the common reservoir, rams, one for each housing arranged across the casing, levers, one for each ram all mounted on a common shaft and means for rocking the shaft to reciprocate the rams in-

cluding two pistons, one adapted to receive steam intermittently as the steam is fed to the engine cylinders, and the other adapted to receive steam constantly from the boiler, the first piston being of larger cross sectional area than the second piston.

28. In a locomotive provided with an air pump and the usual engine cylinders, a plurality of oil feeding devices operated from 10 a common actuator moved in one direction by steam from the boiler intermittently supplied to a piston and in the opposite direction by steam from the boiler constantly supplied to a piston of smaller cross sectional 15 area.

29. In a locomotive provided with an air pump and the usual engine cylinders, a plurality of oil feeding devices operated from 20 a common actuator moved in one direction by steam from the boiler intermittently supplied to a piston and in the opposite direction by steam from the boiler constantly supplied to a piston of smaller cross sectional 25 area, in combination with two sources of such intermittent supply.

30. In a locomotive provided with an air pump and the usual engine cylinders, a plurality of oil feeding devices operated from 30 a common actuator moved in one direction by steam from the boiler intermittently supplied to a piston and in the opposite direction by steam from the boiler constantly supplied to a piston of smaller cross sectional 35 area, in combination with two sources of such intermittent supply, viz., one from an engine cylinder near its admission port and the other from an air pump.

31. In a locomotive provided with an air pump and the usual engine cylinders, a plurality of oil feeding devices, two supplying 40 oil to the engine cylinders and one to the air pump, all of said feeding devices being operated from a common actuator moved in one direction by steam supplied intermittently, either from an engine cylinder or 45 the air pump, and in the opposite direction by steam supplied constantly from the boiler.

32. In a locomotive provided with an air pump and the usual engine cylinders, a plurality of oil feeding devices, two supplying 50 oil to the engine cylinders and one to the air pump, all of said feeding devices being operated from a common actuator moved in one direction by steam supplied intermittently, either from an engine cylinder or the air 55 pump, and in the opposite direction by steam supplied constantly from the boiler, in combination with a three-way cock interposed between the actuator and the two sources of 60 intermittent steam supply.

33. In a locomotive provided with an air pump and the usual engine cylinders, a plurality of oil feeding devices, two supplying 65 oil to the engine cylinders and one to the air pump, all of said feeding devices being

operated from a common actuator moved in one direction by steam supplied intermittently, either from an engine cylinder or the air pump, and in the opposite direction by steam supplied constantly from the boiler, in 70 combination with a three-way cock interposed between the actuator and the two sources of intermittent steam supply, and a device within the engine cylinders oil feeding devices automatically moved by the 75 three-way cock when the intermittent steam supply, coming from the engine cylinder, is shut off.

34. The combination with an oil feeding device comprising an oil channel, a valve 80 adapted to close the channel and steam operated means adapted to actuate the oil feeding means, of a cock for cutting off the steam from such means, and a connection between the same and the channel valve 85 whereby when the movement of the cock is cut off the steam automatically closes the valve.

35. The combination with an oil feeding device comprising an oil channel, a valve 90 adapted to close the channel and steam operated means adapted to actuate the oil feeding means, of a cock for cutting off the steam from such means, and a connection between the same and the channel valve 95 whereby when the movement of the cock is cut off the steam automatically closes the valve, such connection including a rock shaft and a link and lever connection between it and the cock handle. 100

36. In a lubricating device for steam engines lubricant controlling means including two pistons each capable of reciprocating motion and acting against each other, one supplied with steam intermittently and the 105 other constantly.

37. In a lubricating device for steam engines lubricant controlling means including two pistons each capable of reciprocating motion and acting against each other, 110 one supplied with steam intermittently from two different members to be lubricated and the other supplied with steam constantly from one source.

38. In a lubricating device, the combination with a lubricant pump, of means for operating the same, including opposing pistons, means for producing a constant pressure against one piston, and means for producing an intermittent pressure against the 120 other. 115

39. In a lubricating device, the combination with a lubricant pump, of means for operating the same, including opposing pistons having opposite pressure surfaces of 125 different areas, means for producing a constant pressure against the piston having the surface of smaller area, and means for producing an intermittent pressure against the piston having the surface of larger area. 130

40. In a lubricator, the combination with a boiler and an engine supplied therefrom, of a lubricating mechanism for the engine including a pump, and means for operating the pump in one direction by steam supplied from the engine and in the opposite direction by steam supplied from the boiler.
41. In a lubricator, a lubricant propelling pump, means for operating the same comprising oppositely acting piston elements, means for maintaining fluid under pressure against one of the elements to move the

10 pump in one direction, and means for intermittently supplying fluid under pressure against the other piston element to move the pump in the opposite direction and also move the first mentioned piston against the action of the fluid operating thereagainst.

In testimony whereof I affix my signature in presence of two witnesses.

ROBERT WOOD.
